UNITED STATES PATENT OFFICE.

GEORGE T. BOND, OF HUNTINGTON, WEST VIRGINIA.

FLEXIBLE SHAFT.

1,157,148.

Specification of Letters Patent. Patented Oct. 19, 1915.

Application filed October 31, 1914. Serial No. 869,564.

To all whom it may concern:

Be it known that I, GEORGE T. BOND, a citizen of the United States, residing at Huntington, in the county of Cabell and State of West Virginia, have invented certain new and useful Improvements in Flexible Shafts, of which the following is a specification.

This invention pertains to flexible shafts and it has for its objects among others to provide a simple, cheap and novel form of flexible shaft, combining perfect flexibility, uniform throughout the length of the shaft, and in which there is no frictional contact of any part of the shaft against any other part such as always obtains in spirally wound shafts.

I construct the shaft of a flat band, preferably of spring steel, twisted to obtain uniform flexibility throughout. A shaft of this nature is simple in the extreme, more economical to produce and can be made of any desired length or strength.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Figure 1 is an elevation of a shaft constructed in accordance with my present invention, the same being broken away. Fig. 2 is an enlarged detail of one end of the shaft. Fig. 3 is a view at right angles to Fig. 2. Fig. 4 is a similar view showing one end of the shaft attached to a spindle or head. Fig. 5 is an enlarged cross section on the line 5—5 of Fig. 1, looking in the direction of the arrows. Fig. 6 is an enlarged detail of one end of the shaft. Fig. 7 is a similar view looking at the opposite edge.

Like numerals of reference indicate like parts throughout the different views.

In constructing my shaft I take a piece of flat material, preferably spring steel, and, by any suitable machinery or means, twist the same, giving it a uniform twist throughout its length, the twists 1 being

generally in the direction of the length of the shaft and the ends extended axially of the shaft, as seen at 2, to form means for attaching the shaft in the desired position. 55 The end portions 2 may be formed with substantially square shoulders 3 or with the rounded portions 4, as seen in Fig. 3, dispensing with the sharp corners. It is to be noted that the cross sections of the strip at 60 all times have their centers in alinement, the twists being spiral.

If desired, the end 2 of the shaft may be affixed to a spindle or head 5 by inserting the end of the shaft within a longitudinal 65 kerf or slot in the end of the spindle or head and affixing it therein in any suitable manner. It may sometimes be desirable to round the corners of the material of the shaft, as seen at 6, in Fig. 5, so as to avoid 70 sharp angles or corners.

The shaft is easily applied or attached to any driving or driven mechanism; it is so twisted as to insure perfect flexibility throughout its length, which flexibility more 75 over will be uniform. It will also be noted that there is no frictional contact of any part of the shaft against any other part of such shaft and that when power is applied to one end it is immediately transmitted to 80 the other end, without loss of power or of time due to a process of winding up, as in the usual wound types of flexible shaft.

Modifications in details may be resorted to without departing from the spirit of the 85 invention or sacrificing any of its advantages.

A shaft constructed as above described can be used to connect other members whose axes are at an angle to each other instead of in 90 alinement and the shaft is uniformly flexible in all directions throughout its length.

What is claimed as new is:—

1. A flexible shaft composed of a strip of flexible metal having a multiplicity of spiral twists, cross sections of the strip at all points having their centers in alinement with the edges of the strip extending in the direction of the length of the shaft, said shaft being uniformly flexible in all directions throughout its length. 95

2. As an improved article of manufacture 100

a shaft composed of a flat strip of metal having a multiplicity of spiral twists extending throughout its length, cross sections of the strip at all times having their centers in alinement, the edges of the strip extending in the direction of the length of the shaft and the material thereof extending through the axial center of the shaft, said

shaft being uniformly flexible throughout the entire length thereof.

In testimony whereof I affix my signature in presence of two witnesses.

GEORGE T. BOND.
